WALL MATERIAL HOIST

Charles A. McPherson, Edgar, Mont.

Application November 23, 1943, Serial No. 511,450

3 Claims. (Cl. 304—9)

The present invention relates to new and useful improvements in wall material hoists, and has for its primary object to provide, in a manner as hereinafter set forth, novel means for facilitating the application of wallboard, plywood, etcetera, to the ceilings of buildings.

Another very important object of the invention is to provide a hoist of the aforementioned character which, when it is so desired, is adapted to be expeditiously disassembled for storage or transportation.

Other objects of the invention are to provide a hoist of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings, wherein like characters of reference designate corresponding parts throughout the several views, and wherein:

Figure 1 is a perspective view of a hoist constructed in accordance with the present invention.

Figure 2 is a view in vertical section through the device.

Figure 3 is a top plan view.

Figure 4 is a fragmentary view in vertical section, showing the means for frictionally clamping the hoist in adjusted position.

Figure 5 is a view in horizontal section through the standard, taken substantially on the line 5—5 of Figure 2.

Referring now to the drawings in detail, it will be seen that the embodiment of the invention which has been illustrated comprises a base which is designated generally by reference numeral 1. The base 1 includes a four-way fitting 2 which is provided with an upstanding, centrally located coupling 3. The branches of the fitting 2 have threaded thereinto one end portion of comparatively long and short tubular metallic legs 4 and 5, respectively. Smooth tubular braces 6 are welded on the ends of the fitting 2 for preventing breakage of the removable legs 4 and 5 at the points where they are threaded into said fitting. Feet 7 of wood are secured on the outer end portions of the legs 4 and 5, through the medium of clamps 8. The outer end portions of the legs 4 and 5 are provided with openings 9 for the reception of a suitable turning instrument.

A tubular, telescopic sectional standard 10 is

mounted on the base 1. The standard 10 includes a removable lower section 11 which is threadedly mounted in the coupling 3. A reducing coupling 12 connects a comparatively long intermediate section 13 to the lower section 11. The members 11, 12 and 13 have openings 14 therein for receiving a turning tool.

The standard 10 further includes a tubular, vertically adjustable upper section 15 which is slidable in the section 13. A fitting 16 is threadedly mounted on the upper end portion of the section 15. A vertical rod 17 is provided for adjusting the section 15. The rod 17 terminates in a right angularly projecting upper end portion 18 which is engaged in an opening provided therefor in the section 15 above the section 13. At its lower end, the rod 17 terminates in a horizontally projecting handle 19. The lower portion of the rod 17 is fixed in a metallic loop 20 which is slidable on the section 13 of the standard 10.

Threadedly mounted in a boss 21 on the upper portion of the section 13 is a hand-operated set screw 22 for frictionally clamping the section 15 in adjusted position. As illustrated to advantage in Figure 5 of the drawings, the loop 20 is substantially ovate for spacing the rod 17 from the section 13 for passing over the boss 21 when the set screw 22 is removed therefrom when assembling or disassembling the device.

The section 15 is further provided with spaced openings 23 in any one of which a pin is insertible for engagement with the upper end of the section 13 for positively preventing said section 15 from falling should the set screw 22 loosen.

Comparatively long and short tubular metallic arms 24 and 25, respectively, are threadedly mounted in the fitting 16. Tubular braces 26, similar to the elements 6, are provided on the ends of the fitting 16 for the removable arms 24 and 25. Protecting bars 27 of wood, which contact the material, are secured on the arms 24 and 25 by clamps 28. The outer end portions of the arms 24 and 25 are provided with openings 29 for the reception of the turning tool.

It is thought that the operation of the device will be readily apparent from a consideration of the foregoing. Briefly, the hoist is assembled and the material to be applied is placed on the members 27. With the set screw 22 loosened, the section 15 is elevated in the section 13 through the medium of the rod 17 for pressing the material upwardly in position against the ceiling. The set screw 22 is then tightened and, if desired, a pin may be inserted in the opening 23

which is closest to the upper end of the section 13. The material may now be nailed in the usual manner. The construction and arrangement is such that the material may be expeditiously and expertly applied by a single mechanic. If necessary, the section 15 may be rotatably adjusted in the section 13 for positioning the material properly against the ceiling.

It is believed that the many advantages of a wall material hoist constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A wall material hoist of the character described comprising a base, a telescopically adjustable standard mounted on the base, a plurality of horizontal arms mounted on the upper portion of said standard, elongated bars removably mounted longitudinally on the arms, said bars being of appreciably greater width than the arms and having flat upper faces for receiving thereon the material, means for raising and lowering the standard, and means for securing said standard in adjusted position.

2. A wall material hoist of the character described comprising a base including a multi-way fitting, horizontal legs threadedly connected to

said fitting, flat blocks detachably mounted beneath the outer end portions of the legs and constituting feet for the legs, a coupling rising from the fitting, a tubular, telescopically adjustable removable standard threadedly mounted in the coupling, means for vertically adjusting the standard, means for releasably securing said standard in adjusted position, and a plurality of arms mounted horizontally on the upper end portion of the standard and extending rearwardly thereof for receiving and supporting the material.

3. A wall material hoist including a base, a standard on the base, said standard comprising a tubular stationary section and a vertically adjustable section slidably vertically in said stationary section, a vertical rod for adjusting the slidable section, said rod having a lateral finger at its upper end extending through the slidable section and having a handle extending outwardly from its lower end, a loop carried by the rod adjacent the handle and slidable on the stationary section, the rod being held spaced from said stationary section by the loop, a boss upon the stationary section near the upper end thereof, a set screw threaded through the boss for releasably securing the slidable section in adjusted position in the stationary section, and a plurality of arms mounted horizontally on the slidable section for receiving and supporting the material.

CHARLES A. McPHERSON.
